HORS D'OEUVRE DISH

Lois R. Freeberg, Moorhead, Minn.

Application October 14, 1953, Serial No. 27,177

Term of patent 7 years

(Cl. D44—15)

To all whom it may concern:

Be it known that I, Lois R. Freeberg, a citizen of the United States and a resident of Moorhead, in the county of Clay, and State of Minnesota, have invented a new, original, and ornamental Design for Hors d'Oeuvre Dish, of which the following is a specification, reference being had to the accompanying drawing, forming a part hereof.

Fig. 1 is a perspective view of an hors d'oeuvre dish, showing my new design;

Fig. 2 is a side elevational view of the dish element thereof;

Fig. 3 is an end elevational view of that shown in Fig. 2;

Fig. 4 is a top plan view of that shown in Fig. 2;

Fig. 5 is a top plan view of the relish container element of that shown in Fig. 1;

Fig. 6 is a side elevational view of that shown in Fig. 5; and

Fig. 7 is an end elevational view thereof.

I claim:

The ornamental design for an hors d'oeuvre dish, as shown.
